CLAIM

The ornamental design for a Christmas tree ornament with postage stamp, as shown and described.

DESCRIPTION

FIG. 1 is a front elevational view of a Christmas tree ornament with postage stamp showing my new design;
FIG. 2 is a right side elevational view thereof, the left side being a mirror image;
FIG. 3 is a rear elevational view thereof;
FIG. 4 is a bottom plan view thereof, the top being a mirror image.
